VARIABLE THROW CRANK

Original Filed Dec. 19, 1939

FIG. I.

FIG. II.

INVENTOR:

JOSEPH C. WOODFORD,

BY

Arthur E. Paige
Attorney

UNITED STATES PATENT OFFICE

2,281,903

VARIABLE THROW CRANK

Joseph C. Woodford, Wayne, Pa., assignor to John Wood Manufacturing Company, Inc., Conshohocken, Pa., a corporation of Delaware

Original application December 19, 1939, Serial No. 309,949. Divided and this application November 4, 1940, Serial No. 364,265

5 Claims. (Cl. 74—602)

This is a division of my co-pending application Serial No. 309,949, filed December 19, 1939, now Patent No. 2,259,052, for Improvement in fluid meters.

My invention may be conveniently utilized in a meter operated by the flow of liquid in any liquid dispensing apparatus, for instance, in dispensing of lubricating oil or gasoline or other fuel oil. However, the essential features of my invention may be utilized in the construction of a fluid meter of the type disclosed in Letters Patent of the United States No. 2,003,901, granted June 4, 1935, to Parker et al., for Improvement in piston meters.

This invention is an improvement upon that disclosed in my co-pending application Serial No. 290,534, filed August 17, 1939, now Patent No. 2,242,715, wherein Joseph E. Fernly is named as a joint inventor, and relates particularly to the means for securing in adjusted position means for varying the throw of a crank, whereby the length of the stroke of a piston may be varied to vary the amount of fluid passed through the piston cylinder during such stroke. In said pending application the means for the same purpose is a nut on a shaft which is continuously rotated during the operation of the meter. Therefore, as said nut is presented outside of the meter casing in order to be accessible for adjustment, it is necessary to provide a cap cover for it which must be removed to effect any desired adjustment for varying the throw of said crank. On the contrary, in accordance with my present invention the means for effecting such adjustment is carried by a normally stationary shaft and includes a lever fixed upon the end of said normally stationary shaft exterior to the meter casing and having an arcuate slot through which extends a cap screw in engagement with the meter casing, whereby the lever and said normally stationary shaft are secured in any desired position of variance of the throw of the crank.

The form of my invention chosen for illustration is embodied in a positive displacement meter, wherein the crank-shaft is axially aligned with said normally stationary shaft and has rigidly connected therewith an eccentric crank pin; which pin carries a bushing fitted for rotary adjustment thereon, which bushing is a sleeve, having a cylindrical outer surface eccentric to the axis of the pin. Said bushing extends through a bearing in one end of a connecting rod, the opposite end of which is pivoted in the piston, and said bushing has at one end

thereof, beside said bearing, a gear which is concentric with the axis of the crank pin and meshes with a gear which is rigidly connected with said normally stationary shaft. Rotary adjustment of said normally stationary shaft with its gear effects rotary adjustment of said eccentric bushing on said crank pin and in its bearing in the piston rod, with the effect of pre-determining and maintaining the desired length of stroke of the piston until the same is varied by adjustment of said lever.

My invention includes the various novel features of construction, arrangement, and method of operation hereinafter described.

In said drawing: Fig. I is a partly elevational and partly sectional view of a displacement meter conveniently embodying my invention.

Fig. II is an inside elevation of the adjusting lever and gearing shown in Fig. I.

The form of my invention shown in this application differs from that in my original application in that an internal gear is substituted for the external gear fixed on the inner end of the normally stationary shaft shown in the original application and the adjusting lever is of simpler form.

The casing 1 may be of any convenient form having a fluid inlet 2 and outlet 3 for the passage of fluid into and out of the piston chamber 4 in said casing. The crank-shaft 5 is journaled in the bearing 5' in said casing and has the arm 5^a carrying the eccentric crank pin 5^b. Said pin 5^b carries the bushing 6 fitted for rotary adjustment thereon, which bushing is a sleeve having a cylindrical outer surface 6^a eccentric to the axis of said pin 5^b. Said bushing extends through the bearing 7^a in one end of the connecting rod 7, the opposite end 7^b of which is connected with the piston 8 by the pivot 8^a, so that it may be reciprocated in said piston chamber 4. Said bushing 6 has at one end thereof, beside said bearing 7^a, the gear 6^b which meshes with the internally toothed gear 16 which is rigidly connected, conveniently by a pin, with the normally stationary adjusting shaft 10. The web 16' of gear 16 serves as an abutment to prevent axial displacement of the eccentric bushing sleeve 6 and its gear 6^b.

As may be noted from the drawing, the pitch diameter of the internally toothed gear 16 is twice the pitch diameter of the gear 6^b which meshes with said gear 16. Thus, each time the gear 6^b travels a complete revolution of 360° within said gear 16, the piston of the meter is

moved through one complete stroke and returned to initial position.

The adjusting lever 17, is directly engaged by its key 17' with the normally stationary adjusting shaft 10 and held on the latter by the nut 18. As shown in Fig. II; said adjusting lever 17 has the arcuate slot 17^a in coaxial relation with said shaft 10. Said lever 17 may be locked in adjusted position by the lock screw 19 which extends through said slot 17^a into the casing 1, as shown in Fig. I. In that form of my invention; the sealing washer 20 interposed between the hub of the internal gear 16 and the bearing of the shaft 10 in the casing 1 is substituted for the packing with the screw threaded gland shown in the original application.

When the adjusting lever 17 is in the position shown in full lines in Fig. II, the eccentric bushing 6 is in position to afford the maximum length of stroke of the piston rod 7 and piston 8, but, when said lever is adjusted to the position shown in dash lines in Fig. II, said eccentric bushing is adjusted to the position affording the minimum length of stroke of rod 7 and piston 8.

However, I do not desire to limit myself to the precise details of construction, arrangement, or method of operation herein set forth, as it is obvious that various modifications may be made therein without departing from the essential features of my invention as defined in the appended claims.

I claim:

1. In a positive displacement fluid meter having a casing containing a piston cylinder and a piston mounted to reciprocate in said cylinder; the combination with a crank-shaft having an eccentric pin for effecting reciprocation of said piston; of an eccentric bushing sleeve mounted to be turned on said pin and having a cylindrical outer surface in eccentric relation to the axis of said pin; a piston rod pivotally connected with said piston and with said bushing sleeve; an internally toothed gear on one end of said bushing sleeve in concentric relation with the axis of said crank pin; a normally stationary shaft hav-

ing an internally toothed gear rigidly mounted thereon and in mesh with said first gear; a web on said internally toothed gear; means at the outer end of said normally stationary shaft for turning it and thereby varying the eccentricity of the axis of said bushing sleeve with respect to the axis of said crank-shaft; and means for securing said normally stationary shaft in adjusted position in rigid relation with said casing.

5 2. A structure as in claim 1; wherein the means at the outer end of the normally stationary shaft for turning it is a lever, having means holding it in rigid relation with said shaft.

15 3. A structure as in claim 1; wherein the means at the outer end of the normally stationary shaft for turning it is a lever, having means holding it in rigid relation with said shaft; and the means for securing said shaft in adjusted position in rigid relation with the casing, includes a lock screw in threaded engagement with the casing and extending through an arcuate slot in the lever.

20 4. A structure as in claim 1; wherein the normally stationary shaft is in coaxial relation with the crank shaft and internal gear; so that rotation of the crank shaft circularly progresses the bushing sleeve gear in mesh with the internal gear and consequently varies the position of the eccentric bushing on the crank pin, but the pitch 25 diameter of the bushing gear is in such aliquot relation to the pitch diameter of the internal gear that the bushing sleeve is in such position at the discharge end of the stroke of the piston to produce the desired displacement by the piston, indicated by the external setting.

30 5. A structure as in claim 1; wherein the normally stationary shaft is in coaxial relation with the crank shaft and the pitch diameter of the bushing sleeve gear is one-half that of the internal gear in mesh therewith; whereby the bushing sleeve is in such position at the discharge end of the stroke of the piston to produce the desired displacement by the piston, indicated by the external setting.

35 45 JOSEPH C. WOODFORD.
